(57) **CLAIM**

The ornamental design for a self cleaning rake, as shown and described.

DESCRIPTION

FIG. 1 is a top perspective view of a self cleaning rake showing the new design.

FIG. 2 is a bottom perspective view thereof;

FIG. 3 is a top view thereof;

FIG. 4 is a bottom view thereof;

FIG. 5 is a front view thereof;

FIG. 6 is a back view thereof;

FIG. 7 is a side view thereof;

FIG. 8 is a an opposing side view thereof;

FIG. 9 is a top perspective view of an embodiment of a self cleaning rake having a different cleaning element configuration, showing the new design;

FIG. 10 is a bottom perspective view thereof.

FIG. 11 is a top view thereof;

FIG. 12 is a bottom view thereof;

FIG. 13 is a front view thereof;

FIG. 14 is a back view thereof;

FIG. 15 is a side view thereof;

FIG. 16 is a an opposing side view thereof;

FIG. 17 is a top perspective view of an embodiment of a self cleaning rake having yet another cleaning element configuration, showing the new design;

FIG. 18 is a bottom perspective view thereof;

FIG. 19 is a top view thereof;

FIG. 20 is a bottom view thereof;

FIG. 21 is a front view thereof;

FIG. 22 is a back view thereof;

FIG. 23 is a side view thereof; and,

FIG. 24 is a an opposing side view thereof.

Portions of the article shown in broken lines form no part of the claimed design.
